(57) **CLAIM**

We claim the ornamental design for an accessory for aerosol generator, as shown.

DESCRIPTION

FIG. 1 is a top front perspective view of an accessory for aerosol generator.

FIG. 2 is a front elevational view of the accessory for aerosol generator depicted in FIG. 1.

FIG. 3 is a rear elevational view of the accessory for aerosol generator depicted in FIG. 1.

FIG. 4 is a right side elevational view of the accessory for aerosol generator depicted in FIG. 1.

FIG. 5 is a left side elevational view of the accessory for aerosol generator depicted in FIG. 1.

FIG. 6 is a top plan view of the accessory for aerosol generator depicted in FIG. 1; and,

FIG. 7 is a bottom plan view of the accessory for aerosol generator depicted in FIG. 1.
